UNITED STATES PATENT OFFICE.

HENRY A. REDMAN, OF GUTHRIE, OKLAHOMA TERRITORY, ASSIGNOR OF ONE-HALF TO H. R. THURSTON AND JULIA A. THURSTON, OF ROCK, OKLAHOMA TERRITORY.

COMBINATION-PADLOCK.

SPECIFICATION forming part of Letters Patent No. 595,650, dated December 14, 1897.

Application filed August 30, 1897. Serial No. 650,006. (No model.)

To all whom it may concern:

Be it known that I, HENRY A. REDMAN, a citizen of the United States, residing at Guthrie, in the county of Logan and Territory of Oklahoma, have invented a new and useful Combination-Lock, of which the following is a specification.

My invention relates to combination-locks, and has for its objects to provide a simple, 10 strong, and durable construction and arrangement of parts, including the efficient mounting of rotary tumblers when used in connection with a lock of the class wherein a shackle is employed, and also to provide 15 simple means for changing the combinations.

Further objects and advantages of this invention will appear in the following description, and the novel features thereof will be particularly pointed out in the appended 20 claims.

In the drawings, Figure 1 is a view of a lock constructed in accordance with my invention. Fig. 2 is a central sectional view of the same. Fig. 3 is a detail view in perspective of the 25 frame of the lock, the tumblers being omitted. Fig. 4 is a detail view in perspective of the shackle detached. Fig. 5 is a similar view of one of the tumblers detached. Fig. 6 is a transverse section of one of the tumblers 30 and the leg of the shackle.

Similar numerals of reference indicate corresponding parts in all the figures of the drawings.

The body portion or frame of the lock embodying my invention consists of upper and lower caps 1 and 2, connected by front and rear connecting-cheeks 3, the upper cap being provided with twin shackle-leg openings 4, and the lower cap being provided with 35 sockets 5, alined respectively with said openings. Arranged between the upper and lower caps and axially alined respectively with said 40 openings and sockets are twin series of rotary tumblers 6, having bores corresponding in diameter with the shackle-leg openings and 45 alined therewith for the reception of the legs of a shackle 7. The tumblers are provided with inwardly-extending locking-tongues 8, which, when alined, are adapted to register 50 with notches or kerfs 9 in the spaced circum-

ferential enlargements 10 on the legs of the shackle, said tongues each being of a length equal to one-half of the length of the tumbler by which it is carried, whereby when the shackle is in its normal or locked position the 55 tongues occupy positions in the transverse planes of the depressions 11^a between said circumferential enlargements 10.

The tumblers are provided at their contiguous ends with interlocking or rabbeted joints 60 formed by cylindrical extensions 6^c, formed on the tumbler at one end to fit in a rabbet formed in the contiguous end of the adjoining tumbler, the terminal tumblers being mounted, respectively, upon a rabbeted collar 11 and 65 in a ring 12. Each tumbler is provided with exterior alternately-disposed rabbets 6^a and longitudinal grooves or channels 6^b to facilitate the independent turning of the tumblers and to insure the accurate alinement of the 70 characters.

The circumferential enlargements 10 on the shackle-legs preferably consist of longitudinally grooved or kerfed sleeves fitted for revolute adjustment upon the reduced portions 75 of the shackle-legs and adapted to be secured at the desired adjustment by means of set-screws 13, terminally engaging circumferential grooves 14 in the shackle-legs.

When it is desired to change the combination, the tumblers are set to the combination necessary to allow the withdrawal of the shackle. The shackle is withdrawn and the set-screws 13 are loosened, after which the shackle is returned to a position in the lock 85 which arranges the kerf 9 in engagement with the plugs 8 of the tumblers. The tumblers are then turned to arrange their peripheral characters to form the desired combinations, and, finally, the shackle is carefully withdrawn and the set-screws tightened to lock the sleeves at the desired adjustment. It will be understood that the turning of the tumblers will also cause the desired rotary adjustment of the sleeves upon the legs of the 95 shackle.

From the above description it will be seen that each leg of the double or hair-pin shackle is independently locked by a combination of tumblers and both combinations must be 100

properly set in order to release the shackle, thus adding to the efficiency of the lock and increasing the difficulty of opening the same without previously knowing the combination 5 to which the tumblers are set.

Various changes in the form, proportion, and the minor details of construction may be resorted to without departing from the spirit or sacrificing any of the advantages of this 10 invention.

Having described my invention, what I claim is—

1. A lock having a frame comprising spaced terminal caps connected by side cheeks and 15 provided respectively with shackle-leg openings and a corresponding number of alined sockets, a series of revoluble tumblers permanently mounted in the frame between said caps in alinement, respectively, with the 20 alined shackle-leg openings and sockets, and having their contiguous ends connected by interlocking joints, and a double or hair-pin shackle having legs adapted to fit axially in the tumblers, and provided with circumfer- 25 entially kerfed or notched enlargements for engagement by inwardly-extending locking-tongues on the tumblers, substantially as specified.

2. A lock having a frame or body portion, a 30 series of alined tumblers permanently mounted in the frame, and each provided with an inwardly-extending lug and exterior combination characters, and a shackle having a leg adapted to pass axially into the bores of the 35 tumblers and having notched or kerfed enlargements, said enlargements consisting of sleeves independently mounted for revoluble adjustment upon the shackle-leg, and means 40 for securing each sleeve at the desired adjustment, substantially as specified.

3. A lock having a frame or body portion, a 45 series of alined tumblers permanently mounted in the frame, and each provided with an inwardly-extending lug and exterior combination characters, and a shackle having a leg adapted to pass axially into the bores of the

tumblers, and having notched or kerfed enlargements for engagement by the lugs of the tumblers, said enlargements consisting of split sleeves revolubly mounted upon the shackle-leg, and independent set-screws for locking said sleeves at the desired rotary adjustment, substantially as specified.

4. A lock having a frame or body portion, a series of alined tumblers permanently mounted in the frame, and each provided with an inwardly-extending lug and exterior combination characters, and a shackle having a leg adapted to pass axially into the bores of the tumblers, and having notched or kerfed enlargements for engagement by the lugs in the bores of the tumblers, said enlargements consisting of split sleeves mounted for revoluble adjustment upon the shackle-leg, and independent set-screws threaded in the sleeves for 60 terminal impingement upon the surface of the shackle-leg, the shackle-leg being provided in the plane of each set-screw with a circumferential groove or depression, substantially as specified. 7c

5. A lock having a frame, a series of alined rotary tumblers mounted in the frame and having exterior combination characters, a shackle having a leg extending axially through the bores of the tumblers, interlocking means 75 carried respectively by the shackle-leg and tumblers, the means which are carried by the shackle-leg being spaced apart to suit the interval between the tumblers and being mounted for independent rotary adjustment upon 80 the shackle-leg, and locking devices for securing said shackle-carried members of the interlocking means at the desired adjustment, substantially as specified.

In testimony that I claim the foregoing as 85 my own I have hereto affixed my signature in the presence of two witnesses.

HENRY A. REDMAN.
